UNITED STATES PATENT OFFICE.

EARL V. COULSTON, OF CLEVELAND, OHIO, ASSIGNOR OF ONE-HALF TO FRED. H. ZWILLING, OF CLEVELAND, OHIO.

GAS-STOVE.

1,184,828.

Specification of Letters Patent. Patented May 30, 1916.

Application filed March 17, 1915. Serial No. 15,036.

To all whom it may concern:

Be it known that I, EARL V. COULSTON, a citizen of the United States, resident of Cleveland, county of Cuyahoga, and State 5 of Ohio, have invented a new and useful Improvement in Gas-Stoves, of which the following is a specification, the principle of the invention being herein explained, and the best mode in which I have contemplated applying that principle, so as to distinguish it 10 from other inventions.

My invention relates to gas stoves and particularly to the upper part of the gas stove which includes the arrangement of burner, 15 space for receiving the gases of combustion and distribution of heat therefrom in connection with the stove holes.

The general object of the invention is to 20 conserve the heat produced by combustion in the most economical and efficient manner and specifically to control the air supply so that a maximum of heat may be produced and to restrict the zone to which such heat is applied so as to permit the use of a maximum 25 number of stove holes with a minimum number of gas burners.

It has heretofore been customary to form 30 a single large space beneath the top of the stove in which the gas burners were disposed and with which they communicated indiscriminately in all directions, and furthermore the air was permitted to flow in from all sides of the burner without restriction. This arrangement was such that much heat 35 was wasted and to such an extent that it was necessary in order to cook over the stove holes, to provide a gas burner for each of same.

A specific object of the invention therefore 40 is to permit of such a restriction and control of the path of travel of and concentration of the heat of combustion derived from each gas burner, that a cooking operation may be performed efficiently over a stove hole directly beneath which there is no gas burner.

The said invention consists of means hereinafter fully described and particularly set forth in the claims.

The annexed drawing and the following 50 description set forth in detail certain means embodying my invention, the disclosed

means, however, constituting but one of various mechanical forms in which the principle of the invention may be applied.

In said annexed drawing:—Figure 1 represents a plan of a gas stove embodying my invention, with parts removed to disclose the elements beneath such removed parts. Fig. 2 represents a front elevation of the upper portion of the stove. Fig. 3 represents a fragmentary detail longitudinal section taken upon the plane indicated by line III—III in Fig. 1. Fig. 4 represents a fragmentary transverse section of the upper portion of the stove taken upon the plane indicated by line IV—IV, Fig. 1. Fig. 5 represents a perspective view of one of the channel plates. Fig. 6 represents a perspective view of one of the boxes or frames which surround the burners.

The illustrated embodiment of my invention comprises the main frame 1 of the stove, the top of which is provided with two removable plates 2, each of which is formed with two stove holes 3, 3, a front hole and a rear hole, as shown. The usual space 4 is provided above the top 5 of the oven and the top plates 2 which communicate with the outlet flue 6 at the rear and with the atmosphere through the medium of air openings 7, 7, at the front. The burners 8, 8, are disposed in this space 4, at the front and immediately below the front openings 3, as shown, as well as immediately behind the openings 7, 7, in the usual manner. Each of these 85 burners is provided with suitable gas connections connecting it with the main supply pipe 9.

Surrounding each burner is a box 10, open at the top, bottom and front and which rests upon the top plate of the oven 5, the open front being in contact with the front plate 11 of the frame and being secured thereto by means of a bolt 12 which engages a lug 13 formed upon a cross-piece 14, as shown in Figs. 4 and 6, whereby the said box is held securely in place. It will therefore be seen that each of these boxes is of comparatively restricted dimensions so that a comparatively restricted space is formed around each burner for the purpose hereinafter described. Extending forwardly and integrally

formed with the rear of the box is a lug 15 which forms a rest for the rear end of the burner 8, as shown in Fig. 4.

Having its front end resting upon the top 5 of each box 10 is a channel plate 16 consisting of a bottom and two side walls which preferably diverge upwardly. The bottom wall has an intermediate upwardly inclined portion 17 and a rear portion 18 connected 10 therewith, as shown in Fig. 5. A starshaped opening 16^a is formed in the front of this bottom wall to receive the upper portion of the star-shaped burner 8 and to form a restricted opening around same which communicates 15 with the chamber 19 formed around the latter by the walls of the box 10. The side walls of the channel plate extend upwardly to and are in contact with the bottom of the top plates 2 of the stove. This 20 channel plate extends rearwardly a distance such as to bring it at least partially below the rear stove hole 3, as shown in Fig. 5, and at this rear end it communicates with the main space 4 and thus with the outlet 25 flue 6.

The width of the channel plate is such that the sides thereof include the stove holes, but so as to form a space laterally restricted and disconnected from the main 30 plates 4. It will therefore be seen that in addition to the chamber 19, a chamber 20 is formed in the main space or compartment 4 which communicates at the front with the chamber 19 and at the rear with outlet 35 flue.

In the operation of the above described device, the air enters the chamber 19 from the opening 7, passes upwardly around the burner 8 and through the restricted opening 40 formed between the burner and the star-shaped opening 16^a, into the chamber 20. This air, however, entering a restricted chamber and then passing through a restricted opening and into a second restricted 45 chamber, it will be noted that its zone of travel is restricted and that a pronounced draft is thereby created during the combustion of the gas. This results in an increased supply of oxygen being supplied to the gas 50 during combustion, and a maximum production of heat. The products of combustion then pass through the restricted zone or chamber formed by the channel plate and are directed and concentrated toward the 55 area immediately below the second or back stove hole from whence they emerge and are conducted out through the outlet-flue 6. This concentration of these gases of combustion permits of a sufficient application 60 of heat to the space below the second stove hole so that a cooking or heating operation can be conducted upon the latter in an economical and efficient manner.

Having fully described my invention,

what I claim and desire to secure by Letters 65 Patent is:—

1. In a gas-stove, the combination of the stove-frame having its top formed with a front and rear stove-hole, and provided with a compartment beneath such top; a member 70 consisting of side and bottom walls and placed in said compartment so as to form a chamber in the upper part of same beneath said holes; said member formed with an opening in the front of its bottom wall; a 75 member consisting of rear and lateral walls forming a chamber in the front of said compartment and beneath said opening and communicating with the atmosphere; a burner in said second chamber; and an outlet-flue communicating with the back of 80 said first-named chamber.

2. In a gas-stove, the combination of the stove-frame having its top formed with a front and a rear stove-hole, and provided 85 with a compartment beneath such top; a removable member consisting of side and bottom walls and placed in said compartment so as to form a chamber in the upper part of same beneath said holes; said member 90 formed with an opening in the front of its bottom wall; a member consisting of rear and lateral walls forming a chamber in the front of said compartment and beneath said opening and communicating with the atmosphere; a burner in said second chamber; and an outlet-flue communicating with the back of 95 said first-named chamber.

3. In a gas-stove, the combination of the stove frame provided with an upper compartment having an outlet; a removable partition within said compartment and at the front thereof, forming the lateral and rear walls of an interior chamber communicating at the front with the atmosphere; a 100 second removable member within said compartment and having bottom and sides, the front of the bottom of which rests upon the top of said first-named removable partition and the sides of which extend upwardly to the bottom of the top portion of the frame, said second member forming a chamber above said first-named chamber and communicating at the rear with said compartment; the front of the bottom of said 105 second-named member being provided with an opening; and a burner projecting into the latter.

4. In a gas-stove, the combination of the stove frame provided with an upper compartment having an outlet; a partition in the front of such compartment and forming the sides and rear of an interior chamber communicating at the front with the atmosphere; a second member consisting of 120 sides and bottom, the front portion of such bottom resting upon said first-named member and the sides extending upwardly to 125

the bottom of the stove top, said second-named member forming a chamber above said second-named chamber and communicating at the rear with said compartment, 5 the bottom of said second-named member inclining upwardly so as to cause said second-named chamber to be of reduced height at the rear thereof; said bottom being provided with an opening above said first-named

chamber; and a burner projecting into said 10 opening.

Signed by me, this 5th day of February, 1915.

EARL V. COULSTON.
